UNITED STATES PATENT OFFICE.

FRED B. COREY, OF SCHENECTADY, NEW YORK, ASSIGNOR TO GENERAL ELECTRIC COMPANY, A CORPORATION OF NEW YORK.

PROTECTIVE DEVICE FOR SIGNAL SYSTEMS.

No. 839,365.

Specification of Letters Patent.

Patented Dec. 25, 1906.

Application filed August 1, 1904. Serial No. 218,073.

To all whom it may concern:

Be it known that I, FRED B. COREY, a citizen of the United States, residing at Schenectady, county of Schenectady, State of New York, have invented certain new and useful Improvements in Protective Devices for Signal Systems, of which the following is a specification.

My invention relates to block-signal systems for electrically-operated railways; and its object is to protect the relays and other apparatus connected to the rails from injury by the power-current. In electrically-operated railways employing a block-signal system it is customary to sectionalize one of the rails for the purposes of the block-signal system and to leave the other rails continuous to serve as a part of the return for the direct-current power-circuit. If defective bonding exists on the continuous rail, it is evident that a considerable potential may arise between the continuous and sectional rail when a train bridges the defective bond. With the train in this position current would tend to flow from the continuous rail through the axles at one end of the train to the sectional rail and thence back through the axles at the other end of the train to the continuous rail. Since the signal devices including the track-relays and source of current therefore are adapted for low voltages only, a sufficient potential may be produced by the flow of power-current to damage or destroy the relay-winding or source of current. By my invention I employ an electromagnetic overload device connected in series or in parallel with the relay or source of current, or both, and arranged to short-circuit the signal device whenever an abnormal potential occurs between the rails, so that the current through the signal device can never rise to a dangerous amount.

My invention will best be understood by reference to the accompanying drawing, which shows diagrammatically one block of a railway with the signal system arranged in accordance with my invention.

I have shown my invention as applied to an alternating-current-signal system, since alternating current has certain advantages for operating signal systems for electrically-operated railways, both because the alternating current may be readily transmitted along the line, thus saving the expense of

batteries, and because alternating-current apparatus is not liable to be affected by leakage-currents from the rail-circuit. It will be understood, however, that my invention is equally applicable to block-signal systems operated by direct current.

In the drawing, T represents a transformer having its primary connected to the lines L L, which convey the alternating current for energizing the signal system. The secondary of the transformer is connected to the rails, of which the rail R is represented as continuous and the rail R' as sectionalized. A magnet-winding M is connected in series with the secondary of transformer T and controls a switch-contact S, which when magnet M is energized with a certain strength is drawn up and short-circuits the secondary of transformer T. By properly proportioning the magnet-winding M it is evident that the secondary of the transformer T may be short-circuited upon the occurrence of an abnormal potential at the rails, and consequently protected from an excessive flow of power-current. The transformer T is shown as of the open-core type, so that an excessive short-circuit current is prevented.

W represents a relay of the wattmeter type, having its movable winding connected to the other end of the block and its stationary winding energized from a second transformer T'. The movable winding of this relay is protected by means of a second magnet-winding M' and switch-contact S' controlled thereby.

P represents the semaphore-post, on which is a signal which may be controlled by the relay W.

The connections between the relay and the signal are not shown, since they form no part of my present invention and since many operative connections between relays and signal-arms are well known in the art.

It is evident that instead of being connected in series with the relays the magnet-windings M M' may be connected in any other manner which will render them responsive to the occurrence of an abnormal potential on the rails, producing an excessive flow of current through the device to be protected, and the action will be the same in either case.

I have shown protective devices applied both to the track-relay and to the source of

current therefor, and I desire it to be understood that the term "signal device" in the appended claims is intended to include any low-voltage device pertaining to the signal system and connected to the track-rails.

What I claim as new, and desire to secure by Letters Patent of the United States, is—

1. In a block-signal system for electrically-operated railways, a signal device connected to the rails, and an overload-relay adapted and arranged to short-circuit said device upon an abnormal rise of potential between said rails.

2. In a block-signal system for electrically-operated railways, a signal device connected to the rails, a magnet-winding in series with said device, and a switch controlled by said magnet-winding and adapted to short-circuit said device.

3. In a block-signal system for electrically-operated railways in which the rails serve as return-conductor for the power-current, a signal device connected to the rails, and an electromagnetically-operated switch arranged to close a shunt-circuit around said device upon an excessive flow of power-current through said device.

4. In a block-signal system for electrically-operated railways in which the rails serve as return-conductor for the power-current, signal devices connected to the rails at opposite ends of the block, and an electromagnetically-operated switch for each device arranged to close a shunt-circuit around said device upon an excessive flow of power-current therethrough.

5. In a block-signal system for electrically-operated railways in which the rails serve as return-conductor for the power-current, a transformer having its secondary connected to the rails, a resistance inserted between said secondary and the rails, and an electromagnetically-operated switch arranged to close a shunt-circuit across the rails between the rails and said resistance upon an excessive flow of power-current through the transformer-secondary.

6. In a block-signal system for electrically-operated roads in which the rails serve as return-conductor for the power-current, a transformer, leads from the secondary of the transformer to the rails, a resistance inserted in said leads, and an electromagnetically-operated switch arranged to short-circuit said leads between the resistance and the rails upon an excessive flow of power-current in said leads.

7. In a block-signal system for electrically-operated railways, a continuous rail serving as return-conductor for the power-current, a sectional rail, a signal device connected between the rails, and an electromagnetically-operated switch arranged to close a shunt-circuit around said device upon an excessive flow of power-current in said device.

In witness whereof I have hereunto set my hand this 30th day of July, 1904.

FRED B. COREY.
